UNITED STATES PATENT OFFICE.

GEORGE A. WILSON, OF BOSTON, MASSACHUSETTS.

DESIGN FOR A PUZZLE GAME-BOARD.

SPECIFICATION forming part of Design No. 29,855, dated December 20, 1898.

Application filed October 17, 1898. Serial No. 693,834. Term of patent 3½ years.

To all whom it may concern:

Be it known that I, GEORGE A. WILSON, of Boston, in the county of Suffolk and State of Massachusetts, have invented and produced 5 a new and original Design for Puzzle Game-Boards, of which the following is a specification, reference being had to the accompanying drawing, forming part thereof.

The drawing is a perspective view of a game- 10 board illustrating my new design.

The leading feature of my new and original 15 design for puzzle game-boards consists in the design as herein shown and described.

As shown in the drawing, the oblong board 5 has the raised rims or walls 6 6 and 7 7, together forming the outer rim of the board. At one end of the board is the wall 8, extending across the width of the board at a distance

from the nearest rim 7 equal to one-fourth the 20 length of the board. This wall 8 has the opening 9, and from the wall extend the partitions 10 10 to the nearest rim 7. In the center of the space formed by the rims 6 6 and 7 and the wall 8 is a compartment formed by the partitions 11 11, 12, and 13, the partition 13 25 having the opening 14. The distance of the partitions of the central compartment from the rims 6 6 and 7 and from the wall 8 is equal to the diameter of the compartment.

What I claim is—

The design for a puzzle game-board as herein 30 shown and described.

GEORGE A. WILSON.
